UNITED STATES PATENT OFFICE.

EGBERT ALEXANDER, OF BURLINGAME, CALIFORNIA.

REFILLABLE CARTRIDGE-FUSE.

1,198,508.

Specification of Letters Patent. Patented Sept. 19, 1916.

Application filed July 19, 1915. Serial No. 49,793.

To all whom it may concern:

Be it known that I, EGBERT ALEXANDER, a citizen of the United States, and a resident of the city of Burlingame, county of San Mateo, and State of California, have invented a new and useful Improvement in Refillable Cartridge-Fuses, of which the following is a specification.

My invention relates to refillable cartridge fuses as set forth in the Patent No. 1,101,897, issued to me on the 30th day of June, 1914, and the present specification relates to improvements in the construction of the fuse whereby the same may be produced more cheaply and rendered more efficient. I accomplish these several features by means of the device disclosed in the drawings forming a part of the present specification, wherein like characters of reference are used to designate similar parts throughout the said specification and drawings, and in which—

Figure 1 is a broken vertical sectional view of the cartridge disclosing the manner in which the disks are detachably secured to the ends thereof so as to close the said cartridge. Fig. 2 is a plan view of Fig. 1. Fig. 3 is a view similar to Fig. 1 but with the disk removed. Fig. 4 is a plan view of Fig. 3, with the fuse removed. Fig. 5 is a broken front elevation of Fig. 1 disclosing the manner in which one end of the inclosed fuse ribbon extends beyond the disk, and Fig. 6 is a front elevation of the fuse ribbon removed from the cartridge.

Referring to the drawings, the numeral 1 is used to designate a hollow cylinder of any suitable insulating material having the ends thereof provided with metallic caps 2. Approximately one half of the end of each cap 2 is bent back upon the other half as at 3 so as to provide a double thickness of metal. This double thickness enables a greater number of threads to be had in an aperture 4 thereby forming greater security for securing a screw 5 which in turn engages and retains a disk 6 by means of an aperture 7 therein, said aperture 7 being arranged to coincide with the first mentioned aperture 4.

The remaining portion of the end of each cap 2 is extended beyond the double thickness 3 and is formed into a semi-annular flange 8 which is adapted to engage approximately one half of the periphery of

the disk 6 as disclosed in Figs. 1 and 5 of the drawings.

The double thickness 3 has a channel 9 formed therein, as disclosed in Fig. 4 of the drawings, adapted to receive the end 60 of a ribbon fuse 10 which extends, on one end of the cartridge, beyond the edge of the disk 6 and is bent down the side of the cap 2 so as to provide a visible surface whereon the amperes, which the fuse is capable of 65 conducting, may be stamped. The ribbon fuse 10 has a reduced central portion 12 which determines the conductivity of the cartridge.

Rectangular extensions 14 are provided 70 on each disk 6 which is the usual arrangement for fuses above a certain amperage, said extensions 14 being adapted to engage the terminals between which the cartridge is to be inserted.

The space within the hollow cylinder 1 and the ribbon fuse 10 is filled with bismuth or a like substance in order to confine arcing when the fuse 10 is blown out.

The cartridge may be easily and readily 80 refilled by removing the screw 5 and sliding the disk 6 from under the annular flange 8. After the blown fuse has been removed a new one is replaced with the ends thereof in the channel 9. The cartridge may then 85 be refilled with bismuth or a like substance and the disk 6 replaced with one half of the periphery thereof under the annular flange 8. When the screw 5 is screwed into position, the disk 6 will force the ends of 90 the ribbon fuse 10 into the channels 9 thereby tightly closing the cartridge.

In order to properly secure the caps 2 to the cylinder 1 the edges of the said caps 2 are crimped at regular intervals as at 15. 95

It is obvious from the foregoing that I have provided an improved construction for a refillable cartridge fuse whereby the same may be cheaply produced and at the same time rendered accessible for refilling purposes.

Having thus described my invention what I claim as new and desire to secure by Letters Patent is—

1. A refillable cartridge fuse comprising a 105 cylinder of suitable insulating material; a metallic cap secured to each end of the cylinder and having a portion of the end thereof bent back upon itself thereby forming a double thickness of metal, and a semi-annu- 110

lar flange formed on said end; a suitable ribbon fuse connecting the caps; a metal disk engaging the flange; and means securing the disk within the flange and to the double thickness of metal.

2. A refillable cartridge fuse comprising a cylinder of suitable insulating material; a metallic cap secured to each end of the cylinder and having a portion of the end thereof bent back upon itself thereby forming a double thickness of metal and a threaded aperture within said double thickness; a semi-annular flange formed opposite the double thickness; a suitable ribbon fuse connecting the caps; a disk engaging the flange; and a screw screwed into the double thickness of metal and securing the disk within the flange.

3. A refillable cartridge fuse comprising a cylinder of suitable insulating material; a metallic cap secured to each end of the cylinder and having a portion of the end thereof bent back upon itself thereby forming a double thickness of metal, and a channel formed in said double thickness and having a threaded aperture and a semi-annular flange formed opposite said double thickness; a suitable ribbon fuse having the ends thereof engaging the channel in the end of each cap; a disk on each cap engaging the flange thereon; and a screw screwed into each threaded aperture and engaging the disk thereby retaining the ends of the fuse within the channels.

4. A refillable cartridge fuse comprising a cylinder of suitable insulating material; a metallic cap secured to each end of the cylinder and having a portion of the end thereof bent back upon itself thereby forming a

double thickness of metal, and a channel formed in said double thickness and a threaded aperture penetrating the channel and a semi-annular flange formed opposite to each double thickness; a ribbon fuse having the ends thereof within the channels; a disk on each cap engaging the semi-annular flange thereon and the ends of the fuse within the channels; and a suitable screw screwed into the threaded aperture and engaging the disk thereby retaining the ends of the fuse within the channels.

5. A refillable cartridge fuse comprising a cylinder of suitable insulating material; a metallic cap secured to each end of the cylinder and having a portion of the end thereof bent back upon itself thereby forming a double thickness of metal having a channel therein and a threaded aperture penetrating said channel, and a semi-annular flange formed opposite the double thickness; a suitable ribbon fuse having the ends thereof within the channels, one end of said fuse extending beyond the side of the cap and part-way down the side thereof thereby providing a visible surface whereon the amperage of the fuse may be indicated; a disk on each cap engaging the semi-annular flange and the ends of the fuse and having apertures therein coinciding with the threaded apertures in the caps; and a suitable screw screwed into the threaded aperture and engaging the apertures within the disks thereby retaining the said disk within the semi-annular flanges and the ends of the fuse within the channels.

In witness whereof I have hereunto set my signature.

EGBERT ALEXANDER.
